UNITED STATES PATENT OFFICE.

SAMUEL C. WEBB, OF PITTSBURGH, PENNSYLVANIA.

CHECK-LOCK.

1,211,648.

Specification of Letters Patent.

Patented Jan. 9, 1917.

Application filed June 7, 1915. Serial No. 32,592.

To all whom it may concern:

Be it known that I, SAMUEL C. WEBB, a resident of Pittsburgh, in the county of Allegheny and State of Pennsylvania, have invented a new and useful Improvement in Check-Locks, of which the following is a specification.

This invention relates to check locks, and particularly to locks for use on mining cars.

10 In many mines, and especially coal mines, it is the practice to provide each miner or cutter with a number of checks or tokens, one of which he secures to each car of ore or coal mined or cut by him to be removed by 15 the checker at the discharge point as a record of the particular miner's work. These checks or tokens are usually perforated metal disks which are hung on a nail on the car or are inserted in some device or receptacle 20 thereon, said device being so arranged that when the car is tilted or tipped at the discharging point the check is released or unlocked for removal by the checker.

The object of this invention is to provide 25 a check lock of this kind which is of simple construction and design, which can be made at low cost, which is strong and durable and is not liable to be injured or permit injury of the mechanism in service, which protects 30 the check when inserted therein and may be easily manipulated to lock the check therein, which forms an efficient and satisfactory lock to absolutely prevent removal of the check in any other position than when tilted 35 or inclined at the dumping point, and whose interior parts are wholly inclosed or incased and are so constructed and arranged as to prevent unauthorized tampering with the device or the unauthorized removal of a 40 check therefrom.

A further object of the invention is to provide a device of this kind which will also receive and lock a so-called "cutter's check" in addition to the miner's check.

45 Further objects of the invention are in part obvious and in part will appear more in detail hereinafter.

In the drawings, which represent one embodiment of the invention, Figure 1 is a sectional elevation on the line 1—1, Fig. 2, showing the lock applied to the side wall or surface of a mining car, and illustrating the "miners' and cutters' checks" secured therein; Fig. 2 is an elevation of the device removed 55 from the car, as seen from the left in Fig. 1, the parts being shown in their normal posi-

tion; Fig. 3 is a similar view with the parts in the position when the car is tilted or inclined at the dumping point; Fig. 4 is a sectional elevation on the line 4—4, Fig. 1; 33 Figs. 5 and 6 are respectively edge and face views of the miners' and cutters' checks in assembled relation; and Fig. 7 is a face view of another form of check.

Referring to the drawings, the check lock 35 illustrated comprises a casing or body 1 having a front wall 2, parallel side walls 3, a curved or arched roof 4 and a bottom 5, forming a box or container with a hollow chamber 6 therein for the working parts of 73 the device. This box or container is surrounded on its sides and top by a flat flange or rim 7 provided with suitable means for securing the casing to the side wall of the car, such as the perforated bosses 8 to receive bolts or rivets 9 passing through the car wall 10. When the device is attached to the car, as shown in Fig. 1, all of the working parts are therefore completely inclosed within the chamber 6 and are protected 80 from injury or from being tampered with or manipulated by unauthorized persons.

The floor 5 of the casing forms a support for the working parts of the lock, which are attached thereto in any suitable manner, and 85 lie directly over a narrow slot or opening 12 in the floor which extends outwardly in a direction perpendicular to the plane of the car wall when the device is applied thereto, and through which slot or opening the check 90 16 is inserted into the lock. The side walls 3 of the casing depend or extend below the floor 5, and the front wall 2 has a depending slotted ear 17 opposite the outer end of the slot or opening 12, so as to protect the check 95 or checks from injury by external blows when locked to the device, as shown in Fig. 1, and yet leave plenty of room for the fingers in manipulating the check. The slot in ear 17 is not essential with a small check, but enables larger checks than those shown in Fig. 1 to be used, said checks when in locked position then extending into the slot in the ear 17, as will be readily understood.

The locking parts of the device are carried by a suitable support or frame consisting of two members 20 and 21, which have flat faces abutting or meeting in a plane normal to the car wall, and one or both of which is cored out to provide a thin semi-circular cavity or channel 22 between said members to receive the check 16. These two 100 105 110

members are secured to each other in any suitable way, as by rivets or bolts 23, and one or both of them, such as the member 21, may have a laterally extending ear or ears 24 which can be bent into a slot or opening in the other member 20, if desired. This forms a very rigid connection with the members accurately spaced apart so that the cavity or slot 22 is the proper width to receive 10 one and only one check therein.

The support or frame is secured to the casing by bolts or rivets 11 which pass through the floor 5 of the casing and flanges 25 of the members 20 and 21 which rest on 15 said floor, as shown in Fig. 2, and the vertical wall portions of said members which meet to form the cavity for the check may be cut out or otherwise formed on a curve, as shown at 26, Fig. 1, and may have depending end portions extending downwardly through the slot 12, as shown at 27, Fig. 2. The upper portion of one of said members, such as the member 21, is provided with perforated ears 28 to receive a 20 pin 29 which forms a pivot for a movable locking member 30. Said locking member hangs from the pivot pin 29 and swings about the same as an axis, its motion in both directions being caused by gravity. It 25 is provided with a depending hook-shaped portion having an arm 30^a which in normal position of the lock, as when the car is in a horizontal position or on a level track, extends through oppositely disposed openings 31 in the vertical walls of the members 20 and 21. The lower edge of this arm is straight, and in locking position of said member is normal to the plane of the check. Consequently, it cannot be unlawfully manipulated by a thin tool inserted at one side 30 of the check, as it might be if the edge of the locking member were inclined. Each check is provided with an opening 16^a into which the arm 30^a of the locking member 45 moves when opposite said opening, thereby preventing the check from being withdrawn from the device when fully inserted therein. To further insure unauthorized withdrawal of the check, the upper portions of 50 the members 20 and 21 are cored out on their meeting faces to provide a cavity 33 in which is located a compression spring 34 pressing downwardly on a movable plug or abutment provided with a pin or projection 35 extending downwardly through an opening 36 at the bottom of said chamber and in the plane of the slot 22. The projection 35 is of such length that when no check 55 is in the device it extends downwardly into the path of movement of the arm 30^a, so that said projection forms a stop to prevent said arm returning fully to its normal position when a check is withdrawn from the lock. When the check is inserted it lifts the projection and thereby releases the arm 30^a so 60

that it enters the opening in the check when said opening comes opposite said arm. When the check is released from the hand the spring 34 forces it downwardly against the arm 30^a of the locking member and prevents the latter from swinging by gravity to release the check. To further insure unauthorized withdrawal of the check the free end of the arm 30^a is preferably provided with an upwardly extending teat or projection 37, forming a shoulder which will engage with the check if the arm by any chance should happen to move toward check releasing position. 70

The outer edge of the locking member 30^a 80 may be provided with an outwardly extending arm 38 arranged to engage a shoulder or abutment 39 on one of the members 20 or 21 when the locking member is in locking position, as in Fig. 4, and thereby prevents it from moving too far. Said member may also be provided beneath said arm 38 with a shoulder 40 which engages the abutment 39 in moving to check releasing position. This abutment 39 prevents unauthorized manipulation of the lock, such as by a workman pressing upwardly on the check and striking the casing a blow with a hammer to cause the locking member to swing to release position. In so doing it strikes the abutment 39, 90 or, if desired, may be so arranged as to strike the side casing wall 3, and the quick rebound of said member to locking position prevents the miner from removing the check from the device. This arrangement therefore forms a 100 very secure lock for the check and prevents unauthorized removal of the check by one miner and substitution of his own check therefor before the car reaches the checker at the dumping station. 105

In use of the device the miner inserts his check with the cutter's check attached thereto if necessary into the slot in the bottom of the device and pushes the check up until locked therein. When the car reaches the 110 dumping place outside the mine it is tipped or tilted to an inclined position, which position it never reaches until the dumping operation. When the car is in the inclined position the lock is in the position shown in 115 Fig. 3, and while in said position the checker grasps the check and pushes upwardly against the pressure of the spring 34. This enables the locking device 30^a to swing by gravity to the position shown in Fig. 3 and 120 the check or checks to be withdrawn from the lock. When the car is tilted back to normal position the locking arm 30^a engages the projection 35, which holds it back until the projection is lifted by inserting the next 125 check.

This lock may be used with the ordinary flat circular perforated check, as shown in Fig. 7, but special checks may be provided therefor, if desired, such for example, as 130

the checks shown in Figs. 5 and 6. In these views the miner's check 16 is shown pressed to form one or a plurality of vertical ribs or corrugations 41, to engage corresponding channels or grooves 42 in the walls of the cavity 22, to thereby guide the check to proper locking position and insuring the insertion of the check into the device in proper position. The cutter's check 43 is provided at one point in its periphery with a tongue which is bent back upon the body of the check to form a hook 43^a. When a cutter's check is to be locked in the device the hook 43^a is slipped into the opening of the check in the position shown in Fig. 6 with the cutter's check hanging from the miner's check 16. The miner's check is then inserted into the lock, as shown in Figs. 1 and 4, in which position the major portion 20 of the opening 16^a is within the walls of the frame members 20 and 21. In this position the exposed portion of the opening 16^a is too small to enable the cutter's check to be removed from the miner's check, so that both checks are effectively and securely locked to the device.

This check lock is of simple construction and entirely prevents unauthorized removal of a check by any person in any way, as all the working parts are inclosed and are so arranged as to prevent unauthorized manipulation thereof. It consequently insures a correct credit to each miner or cutter for the work done by him and thereby prevents frequent disagreements between employer and employee.

What I claim is:

1. A check lock, comprising a casing having a chamber therein and provided with a slot to receive a check, a hollow support therein, a depending freely swinging locking member carried by said support and arranged to engage a check, and a movable abutment in the cavity of said support for temporarily preventing said locking member from moving to locking position.

2. A check lock, comprising a hollow casting for attachment to a car side and provided with a slot to receive a check, a support therein, a depending locking member carried by said support and arranged to engage an opening in said check, means for

exerting downward pressure upon said check to prevent disengagement of the locking device therefrom, and a projection on 55 said locking member arranged to prevent accidental withdrawal of said member through the check opening.

3. A check lock, comprising a casing provided with a slot to receive a check, a support therein provided with a check receiving cavity, a yielding abutment above said cavity for engaging the check, and a swinging locking device having an arm arranged to move across the plane of said cavity beneath said abutment.

4. A check lock, comprising a casing provided with a slot to receive a check, a support therein provided with a check receiving cavity, a yielding abutment above said 70 cavity for engaging the check, and a swinging locking device having an arm arranged to move across the plane of said cavity beneath said abutment, said abutment when projected extending into the path of movement of said arm and forming a stop to temporarily prevent it from moving to locking position.

5. A check lock, comprising a casing having a cavity to receive a check, the walls 80 of said cavity being provided with channels, means carried by the casing arranged to engage the check to lock the same, and a check provided with ribs arranged to engage the grooves of said cavity for guiding 85 the check to locking position.

6. A check lock, comprising a casing having a cavity to receive a check, the walls of said cavity being provided with channels, means carried by the casing arranged to 90 engage the check to lock the same, a check provided with ribs arranged to engage the grooves of said cavity for guiding the check to locking position, and a cutter's check having a hook-shaped portion at its edge 95 adapted for insertion into the opening in said first named check.

In testimony whereof, I have hereunto set my hand.

SAMUEL C. WEBB.
